UNITED STATES PATENT OFFICE.

JOHN VIDAL, OF BROOKLYN, NEW YORK.

EMBROIDERY-FRAME.

1,263,164.

Specification of Letters Patent.

Patented Apr. 16, 1918.

Application filed December 5, 1917. Serial No. 205,636.

To all whom it may concern:

Be it known that I, JOHN VIDAL, a citizen of the United States, residing at Brooklyn, in the county of Kings and State of New 5 York, have invented new and useful Improvements in Embroidery-Frames, of which the following is a specification.

This invention relates to embroidery frames or the like and has for its principal 10 object the provision of means for securing the cloth in position upon the frame so as to prevent marring of the edges thereof and at the same time furnishing means which can be expeditiously adjusted to permit of 15 the application of the cloth to or removal of the same from the frame.

Another object of the invention resides in the provision of a device of this character 20 in which the edges of the cloth can be uniformly engaged with the frame so as to hold the working surface of the cloth in a substantially applied condition throughout.

Another object of the invention resides in the provision of an embroidery frame or the 25 like which is provided with a cloth receiving groove and flexible means adapted to be extended into said groove and against the marginal edge of the cloth to hold the same in an applied position, supplementing said 30 means with a tensioning device whereby the means may be brought under the requisite tension to positively assure retention of the cloth in the groove.

With the above and other objects in view 35 which will appear as the nature of the invention is better understood, the same consists in the improved construction and novel arrangements of parts which will herein-after be fully described and particularly 40 pointed out in the claims.

In the accompanying drawings has been 45 illustrated, a single and preferred form of the invention, it being, however, understood that no limitations are necessarily made to the precise structural details therein exhibited, but that changes, alterations and modifications within the scope of the claims 50 may be resorted to when desired.

Figure 1 is a plan view of the frame.

50 Fig. 2 is a side view thereof.

Fig. 3 is an end view thereof.

Fig. 4 is a sectional perspective view of a portion of the frame.

Fig. 5 is a transverse section through one 55 of the bars of the frame,

Fig. 6 is a horizontal section through one of the bars of the frame showing the tensioning mechanism and flexible retainer.

Fig. 7 is a similar view showing a slightly modified form of the invention.

The invention, while being particularly applicable for use in connection with embroidery frames, is nevertheless most effective for the purpose generally of clamping cloths, hides, and the like in usual 60 stretching frames and the like. In view thereof, I do not desire to limit myself to the use of the invention in connection with embroidery frames.

Structurally, the frame shown herein consists of side bars 8-8, and end bars 9-9, each having a continuous slot 10, therein. The end bars are adjustable angularly with 65 relation to the side bars through the slotted formation described, the said slots receiving 70 clamping bolts 11, of any suitable well known design which can be actuated to permit various adjustments of the frame to be made and which will also operate to hold the mating bars of the frame in relatively 75 fixed positions after a desired adjustment has been obtained.

The essential feature of the present invention resides in mechanism for clamping the cloth in the frame. In order that this can 80 be accomplished without marring the edges of the cloth, and the marginal edges of the latter uniformly held in a firmly clamped position upon the frame, I provide each of the mentioned bars 8-8, and 9-9, with a 85 longitudinally extending groove 12. In addition thereto, I provide each bar with a flexible clamping element or connection 13, connected at 14, at its ends to the bar and associated with tensioning means 15, which 90

in this instance, are substantially of bolt formation having shanks 16, extended through transverse slots 17, in the bar and winged nuts 18, for holding the bolts against sliding movement. The outer end of each 100 of said bolts is provided with a head 19, which is adapted to be advanced against the connection 13, and place the same under tension. Said head is provided with a toothed surface 20, adapted to be brought 105 into co-acting relation with a fixed rack bar 21, on the frame bar as shown in Fig. 6. Through this arrangement the bolt 16, can be adjusted so as to advance the toothed surface 20, against the rack bar and the re- 110

lation thus set up will positively operate to hold the head 19, against casual derangement from a selected adjusted position.

Each connection 13, is arranged normally 5 at one side of the grooved portion of the bar with which it is connected so that it may be manipulated by hand and projected into the groove as shown in detail in Fig. 5. The grooves in the bars of said frame are preferably under-cut.

10 In use, I employ relatively stiff rods 22, around which the marginal edges of the cloth are adapted to be looped as illustrated in Fig. 5. The said marginal edges are then 15 made to traverse the grooves in the bars of said frame and finally the flexible connections 13, are placed against said marginal edges and projected into the mentioned grooves 12. Under the resilient action of 20 said connections 13, the said marginal edges of the cloth are uniformly held in secured positions upon the frame as will be readily understood. The rods 22, give rigidity to the marginal edges of the cloth and assist 25 materially toward setting up uniformity of clamping action between the frame and the cloth.

After the flexible connections have been 30 placed in the grooves, they may be brought under any desired tension by the devices 15, at the corners of the frame. This arrangement is such that the cloth can be expeditiously applied to or removed from the frame; it can be uniformly held in a 35 stretched condition, and the marginal edges of the cloth will not in any way be marred or injured through the clamping of the same to the bars of the frame.

The rods 22, are preferably of cylindrical 40 formation and each extends preferably the full length of the groove in which it is fitted. The flexible clamping elements 13, are preferably non-metallic and non-corrosive. In practice I find ordinary rope to 45 be most suitable for the purpose for which the tensioning connections 13, are employed.

In the modified form of the invention shown in Fig. 7, the frame bar 23, is provided with a projection or head 24, which 50 is equivalent of the head 19. The bar is provided with a slot 25, and operating therein is a screw 26, having a manipulating portion 27, at the corner bar. Said screw

has swivel connection at 28, with the flexible clamping means 29. By adjusting the screw, 55 the connection 29, can be brought under any desired tension in order that the looped portion of the cloth can be satisfactorily adjusted into the under-cut portion of the groove 12, hereinbefore referred to. This 60 same operation of parts applies to the first embodiment of the invention in that under the natural tendency of the elements 13, to move toward the center of the frame, the marginal edges of the cloth will be always 65 advanced into the under-cut portions of the cloth receiving grooves.

What I claim is:

1. An embroidery frame having a cloth receiving groove, flexible means adapted to 70 be associated with the cloth and inserted therewith in said groove to hold the cloth in an attached condition upon the frame, and a relatively stiff bar adapted to receive the cloth in loop form and uniformly maintained contact thereof with said flexible means.

2. An embroidery frame having cloth receiving grooves, and relatively stiff elements 80 adapted to be rolled in the marginal edges 85 of the cloth and insertable therewith in said grooves, and flexible devices normally disposed at the sides of said grooves and insertable therein to hold said elements against casual displacement from said grooves when 90 the cloth is stretched in the frame.

3. An embroidery frame consisting of a plurality of bars each having a groove extending in one of its longitudinal faces, a non-metallic flexible clamping element carried by each bar and adapted for insertion in the groove of said bar, the groove serving to receive the marginal edge of the cloth therein, said clamping element serving to retain the edge of the cloth in said groove, 95 and means carried by each of said bars for tensioning the flexible element thereof to regulate its pressure against the marginal edge of the cloth when the latter is positioned in the groove, said element being 100 adapted to occupy a position directly at one side of the groove before an application of the cloth to the frame.

In testimony whereof I affix my signature.

JOHN VIDAL.
